(57) **CLAIM**

The ornamental design for a battery connecting port cover, as shown and described.

DESCRIPTION

FIG. 1 is a perspective view of the battery connecting port cover with a battery shown in broken lines;

FIG. 2 is a front view thereof;

FIG. 3 is a bottom view thereof;

FIG. 4 is a top view thereof;

FIG. 5 is a left side view thereof;

FIG. 6 is a right side view thereof; and,

FIG. 7 is a rear view thereof.

The broken lines are for the purpose of illustrating a battery to which the battery connecting port cover is secured and forms no part of the claimed design.
